The ornamental design for a absorbant mat for catching foods thereon, as shown and described.

DESCRIPTION

FIG. 1 is a top plan view of a absorbant mat for catching foods thereon showing our new design;

FIG. 2 is a bottom plan view thereof;

FIG. 3 is a side elevational view thereof;

FIG. 4 is a front elevational view thereof; and,

FIG. 5 is a perspective view thereof.

The broken line showing of a high chair is for illustrative purposes only and forms no part of the claimed design.
